UNITED STATES PATENT OFFICE.

HIRAM S. MAXIM, OF BROOKLYN, NEW YORK.

ELECTRICAL IGNITING DEVICE FOR GAS-ENGINES.

SPECIFICATION forming part of Letters Patent No. 296,341, dated April 8, 1884.

Application filed January 12, 1884. (No model.) Patented in France October 6, 1883.

To all whom it may concern:

Be it known that I, HIRAM S. MAXIM, a citizen of the United States, and a resident of Brooklyn, in the county of Kings and State of New York, have invented certain new and useful Improvements in Electrical Igniting Devices for Gas-Engines, of which the following is a specification, reference being had to the drawings accompanying and forming a part of the same.

My invention relates to apparatus for effecting the ignition or explosion of gaseous mixtures in gas engines or motors by means of an electric spark.

The objects of the invention are to simplify the construction and to render more certain the action of the devices for accomplishing this, and to avoid the employment of the galvanic or similar generators which have been required hitherto.

The main features of my invention are the following: Upon the legs of a strong permanent magnet, or the cores of an electro-magnet, I place bobbins of insulated wire containing a number of layers or convolutions. In face of the poles of this magnet I arrange an armature, pivoted in such position as to be encountered by a moving part of the engine at the proper moment, and detached from the poles to which it is held by magnetic attraction. Within any part of the explosion-chamber of the engine are placed two contact strips, pins, or the like, one of which is connected with the pivoted armature in such manner as to be moved by the retraction of the same out of contact with the other. The ends of the wire composing the bobbins are connected to the strips or contact-points, and the latter are properly insulated. These devices are so arranged that the armature will be encountered by the part of the engine designed for that purpose at the moment when it is desired to produce the explosion of the gaseous mixture under the piston of the engine. The movement of the armature away from the magnet induces a current in the coils surrounding the latter, which current being interrupted by the separation of the contact-points within the explosion-chamber produces a spark which ignites the charge of gas.

This invention, the general nature of which

I have now described, is applicable to many varieties of gas motors or engines. In more particularly describing the construction and operation of the same, however, I will refer to 55 the accompanying drawings, which illustrate a special form of engine invented by me, and to which my improved exploder is applied.

Figure 1 is a central vertical section of the engine complete. Fig. 2 is a modified form 60 of magnet to be used with the exploding devices, and Fig. 3 is a sectional view of a detail.

A and B are two pistons, the piston B having an area of rather more than twice that of 65 piston A. These two pistons are cast in one piece, and are connected to a piston-rod which operates a crank-shaft, C C. The pistons work in a vertical cylinder, which is cast in one piece, and has a portion, B', of sufficient di- 70 ameter to receive the piston B, and a smaller portion, A', in which works the piston A.

Below the piston A is a space, T, known as the "explosion-chamber" in engines of this character. This explosion-chamber and the 75 portion of the cylinder A' are surrounded by the usual water-jackets, S, through which a circulation of water is maintained during the operation of the engine.

On the crank-shaft C is placed a pulley- 80 wheel and a fly-wheel. In the latter is a frame, K K, supporting a hinged weight, H, which is held to the hub of the fly-wheel by means of a stout spiral spring, p.

Through a projection from the hub of the 85 fly-wheel passes a spindle, J, on which is a loose sleeve formed with a rim, I, the whole constituting a shifting-roller. An arm, r, extending from the weight H, engages with this roller. The tension of the spring p is adjusted 90 by means of a set-screw, q. These parts constitute the governing mechanism, and their functions will be explained more fully herein-after. Entering the space T below the piston A is a passage, D, connected to a chamber, u, into which extends the perforated end of a gas-pipe, E. A valve, F, kept closed by a spring, is placed at the upper end of chamber u. Communication between the passage D and chamber u is closed by a valve, O, the 100 stem of which passes through the wall of chamber u, and is surrounded by a spiral spring, i.

G is a bell-crank lever, pivoted to a support on the base of the engine. One end of this lever bears upon the end of the stem of valve O. The other end of lever G is connected to a rod, M, the end of which is turned back upon itself. A wheel or pin, L, is placed on the cylinder or other convenient part of the engine, and serves to keep the rod M in place, while permitting it to move freely up and down. 15 In the normal operation of the engine, the rounded or beveled end of rod M lies in the path of movement of the roller I.

In the bottom of the cylinder T is a spring-valve, P, opening inward for the admission of air, and in the passage D is a smaller valve, e, for a similar purpose.

Between the two portions A' and B' is an enlargement containing an annular space, U. Above this space is a ring, K, of the same 20 diameter as the portion A' of the cylinder. Above this ring is a second annular space, V, from which leads a pipe containing an exhaust-valve, (not shown in the drawings,) provided with a spiral spring, the tension of which may 25 be adjusted in any ordinary manner.

The operation of an engine constructed in the manner described is as follows: The proper connections are made with the gas-main and a circulation of water started in the jacket S. 30 The pistons A B are then set in motion by revolving the crank-shaft C. As the piston A ascends, it draws in air through the valves P and e. The springs which close the valves, however, prevent a full atmosphere entering. 35 A partial vacuum is thus produced in the cylinder A'. The piston B in its upward movement also produces a partial vacuum in the chamber or annular space V. When it has reached a point where the piston A is wholly 40 withdrawn from its cylinder, there is a full connection established through the annular space U into the chamber V. The air passes freely, therefore, from one chamber to the other until the same degree of vacuity exists in the 45 chamber T as exists in the space or chamber V. As the crank-shaft is rotated, the piston A descends and closes off the communication between the cylinder A' and the space U. At this moment the roller I is brought in contact 50 with the end of rod M, which, operating through the bell-crank lever G and the adjusting-screw N, presses the valve O open, thus admitting sufficient gas or gas and air through O to bring the pressure in the exploding-chamber T to one atmosphere. The 55 descent of the piston A compresses the gases in the cylinder A' until a pressure of about forty pounds is attained. At this moment the exploding device is brought into operation and the gaseous mixture ignited. By the force of the explosion the piston is driven upward with great force. As it passes in its upward stroke beyond the space U, the gas below it will be instantly sucked out into the 60 chamber V, and as there is not gas sufficient 65 to fill this chamber air will be drawn in

through P and e. Then, when the piston descends again, the space beneath it will be partly filled with pure air, until the piston has reached a point where the valve O is opened 70 as before, when sufficient gas will enter at O to produce one atmosphere of explosive mixture at T. It is desirable that a small proportion of air should enter the explosion-chamber along with the charge of gas. For this 75 purpose the valve F is employed.

The operation of the governor is similar to those described by me in other applications, the principle of operation being to regulate the number of charges rather than the quality 80 of each individual charge. It will thus be understood that any increase above the normal speed of the engine will cause the weight H to recede from the hub of the fly-wheel by centrifugal action, in this way shifting the sleeve 85 or roll I out of line with the plate M, so that the latter is not depressed, and the valve O in consequence not opened until the normal speed has been again reached, when the roller I will be brought back into position to operate the 90 rod M.

Having now described the general character and operation of the engine, I will describe the igniting devices which constitute the invention.

R is a horseshoe-magnet secured in a convenient manner to the frame or cylinder of the engine. Upon the ends of this magnet are coils of insulated wire, R'. Below the poles of the magnet is a pivoted lever, r', carrying an armature, s. Passing through the walls of 95 the passage D are two metal pins, a' b'. The lower pin, b', passes through a screw-plug, e, and bushing e', both of insulating material, and is fitted in such way as to be capable of adjustment. The pin a' passes through a screw-plug, a, of insulating material, which has a perforation of sufficient diameter to permit the said pin to move freely through it. The pin a' passes through a perforation in the end of the armature-lever, and has a head, d. These 100 parts are so adjusted that when the armature s is in contact with the poles of the magnet, or is drawn up to its highest position by the same, the pins a' b' will be in contact, but will be separated by the retraction of the armature by 105 the raising of the pin a'. The ends of the coils R' are connected to the pins—one directly to the pin b', the other by means of a spring, f, attached to the lever r' and bearing on the 110 head of pin a'. 115

W is a rod held by one or more guides, x, secured to the frame or cylinders of the engine. The lower end of this rod passes through a 120 perforation in the long arm of the lever r', and is provided with an adjustable nut, v.

W' is a bar joined to the upper end of rod W, and carried around the shaft C, on which is a cam, f', that raises the bar during a portion of the revolution of the engine, and permits it to suddenly drop at the moment when 125 the charge is to be exploded in the cylinder T.

To insure the proper action of the bar, a

spring, *b*, secured to the cylinder or frame of the engine, presses the bar *W'* or rod *W* downward.

The operation of these parts will be readily understood. Normally the pins *a' b'* remain in contact. By the movement of the engine the charge of air and gas is admitted to the space *T* and the passage *D*. When the piston *A* has reached the desired point in its descent, 10 the bar *W'* and rod *W* are dropped by the cam *f'* and the spring *b*, the armature suddenly retracted from the poles of the magnet, and a current induced in the coils *R'*, which flows through the pins *a' b'*. Simultaneously with 15 the development of this current the pin *a'* is raised from pin *b'*. This gives rise to a spark between the two that explodes the charge.

The construction described is given merely as an example of many similar forms that may 20 be used.

I do not confine myself to the use of any special form of contact pins or strips, nor to the specified means of effecting their separation. It is obvious, too, that the character 25 and arrangement of the magnet, the coils, and armature, which together constitute a magneto-electric generator, may be greatly varied. For example, an electro-magnet may be used in lieu of a permanent one, and any 30 means employed of effecting the separation or withdrawal from its poles of the armature; but,

Having described the main and essential features of the invention and the manner of applying the same to an engine, what I claim 35 is—

1. The combination, with a gas-engine, of a magnet and movable armature-coils upon the magnet, a circuit carried through the chamber or space for containing the explosive 40 charge, and mechanism connected with a moving part of the engine and operated thereby

for causing a sudden movement of the armature and breaking the circuit within the explosion-chamber, all substantially as set forth.

2. The combination, with a gas-engine, of 45 separable contact-pins arranged within the chamber or space for containing the charge, a magnet with coils in circuit with said pins, a movable armature connected with one of the pins, and mechanism connected with a moving part of the engine and operated thereby for effecting the retraction of the armature from the magnet and the separation of the pins within the explosion-chamber, all substantially as set forth. 50

3. The combination, with a gas-engine, of separable contact-pins arranged within the chamber or space for containing the charge, a magnet with coils in circuit with said pins, a movable armature connected with one of the 60 pins, and a rod operated by a cam on the shaft of the engine for effecting the withdrawal of the armature from the magnet and the separation of the pins within the explosion-chamber, all substantially as set forth. 65

4. The combination, with a gas-engine, of separable contact-pins arranged within the chamber or space for containing the charge, a magnet with coils in circuit with said pins, a movable armature connected with one of the 70 pins, and a spring-actuated rod operated by a cam on the shaft of the engine for effecting the withdrawal of the armature from the magnet and the separation of the pins within the explosion-chamber, all substantially as set forth. 75

In testimony whereof I have hereunto set my hand this 17th day of December, 1883.
